(74) Attorney, Agent, or Firm—Richard J. Veltman; John D. DelPonti

(57) **CLAIM**

The ornamental design for a spout, as shown and described.

DESCRIPTION

FIG. 1 is a perspective view of the new design for a spout; FIG. 2 is a left elevational view of the new design for a spout, the right elevational view being a mirror image; FIG. 3 is a top plan view of the new design for a spout; FIG. 4 is a bottom plan view of the new design for a spout; FIG. 5 is a front elevational view of the new design for a spout; and, FIG. 6 is a rear elevational view of the new design for a spout.

The broken lines in FIG. 4 are for illustrative purposes only and form no part of the claimed design.
